US0D1092504S

(12) **United States Design Patent** (10) Patent No.: **US D1,092,504 S**
(45) Date of Patent: ** Sep. 9, 2025

(54) **DISPLAY PANEL WITH GRAPHICAL USER INTERFACE**

(71) Applicant: **Samsung Display Co., Ltd.**, Yongin-si (KR)

(72) Inventor: **Che Ryong Hwang**, Yongin-si (KR)

(73) Assignee: **Samsung Display Co., Ltd.**, Yongin-si (KR)

(**) Term: **15 Years**

(21) Appl. No.: **29/888,025**

(22) Filed: **Mar. 27, 2023**

(30) **Foreign Application Priority Data**

Feb. 23, 2023 (KR) 30-2023-0006852
